UNITED STATES PATENT OFFICE.

WALTER D. DRYSDALE AND ALEX DOW, OF DETROIT, MICHIGAN.

HEAT ECONOMIZER FOR CONDENSING PRIME MOVERS.

Application filed October 15, 1919. Serial No. 330,782.

To all whom it may concern:

Be it known that we, WALTER D. DRYSDALE and ALEX Dow, both citizens of the United States of America, residing at Detroit, in the county of Wayne and State of Michigan, have invented certain new and useful Improvements in Heat Economizers for Condensing Prime Movers, of which the following is a specification, reference being had therein to the accompanying drawings.

The invention relates to heat economizers for condensing prime movers, and its object is to save the heat in the drip discharge from a prime mover of this type.

It is essential to provide the different pressure stages of a condensing prime mover (such as the successive cylinders of a condensing steam engine, or the different stages of a condensing steam turbine) with drips to get rid of the water which, if allowed to accumulate, would interfere with the moving parts of the prime mover, but it is usually necessary to allow some steam to escape at the same time, which is especially true when the pressure in the pressure stage is below the atmospheric pressure. The drip system of a large prime mover, if equipped with steam traps throughout, becomes very much complicated and if any of these traps cease to function, a serious accident may arise through accumulation of the water.

Heretofore, drips from pressure stages in which the pressures are below that of the atmosphere have been connected directly to the condenser through restricted openings, thereby permitting a small constant flow of mixed water and steam and keeping the pressure stages free of any accumulation of water. The sensible heat of the mixture of steam and water forming the drip charge and the latent heat of steam is lost when it is discharged into the condenser, because it is transferred to the circulating water of the condenser and thus thrown away. To avoid this loss the drips are sometimes led to a vaporizer or to an auxiliary condenser system, or some equivalent device, whereby the heat of the drip discharge is transferred to the feed water on its way to the boilers. The use of such a system, however, becomes as complicated as the use of a multiplicity of steam traps and it has not the advantage of being a self-contained part of the con-

densing prime mover operating only when the prime mover is in service.

With our invention the sensible heat of the mixture of steam and water and the latent heat of steam is saved, and furthermore the system is a self-contained part of the condensing prime mover, which operates only when the prime mover is in operation.

Other objects of the invention reside in further advantages as more fully herein-after set forth.

In the drawings:

Figure 1 is a side elevation partly in section of a condensing prime mover embodying our invention;

Figure 2 is a side elevation showing a portion of a modified construction;

Figure 3 is a top plan view showing a portion of still another modified construction;

Figure 4 is a cross section on line 4—4 of Figure 3.

Figure 5 is a cross section on the line 5—5 of Figure 1.

Our invention is particularly applicable to condensing prime movers using surface condensers wherein the condensate (that is to say, the water formed by the condensation of steam after its passage through the condensing prime mover) accumulates in the bottom of the condenser or in an extension thereof, commonly known as a hot well. This condensation is in most cases three to ten degrees colder than the temperature of re-evaporation corresponding to the pressure within the condenser, but the effort of operators is to have its temperature as high as possible and preferably at the upper limit.

In general, our invention consists of arrangements and devices whereby the drip discharge from the condensing prime mover can be mixed with the condensate and the whole heat of the drip discharge thereby saved. Inasmuch as the condensate is used as feed water in the boilers whatever extra heat is put into it before its arrival at the boilers saves adding the same amount of heat in the boilers by the burning of more coal. It is obvious that if the heat added by the drip discharge raises the upper portion of the condensate above the re-evaporation temperature the vapor thus released will be condensed by the circulating water in the condenser and the heat thereby lost.

- In detail, and as shown in Figure 1, 1 is the condensing prime mover, which in the present instance is a steam turbine having the pressure stages 2, 3 and 4, into which 5 the steam enters through the valve 5. 6 is a surface condenser for condensing the steam after its passage through the turbine and 7 is a hot well at the bottom of the condenser for receiving the condensate. 10 8 is a pump for withdrawing the condensate from the hot well 7 through the discharge opening 9 located near the bottom of the hot well. 10 are drips connecting into the pressure stages 2, 3 and 4, the function of these drips being to free the pressure stages of the water therein. Steam as well as water may pass through these drips, the purpose of the steam being to eject the water from the pressure stages. 15 20 In order to save the heat in the discharge passing through the drips 10, and in order to make the system a self-contained part of the turbine which operates only when the turbine is in operation, the following construction is provided: 11 is a pipe which communicates with suitable pipe connections 12 leading from the drips 10. This pipe 11 extends into the hot well 7 and is provided with a suitable injector 13 at its end with 25 30 in the hot well. The longitudinal axis of the injector is substantially parallel to the direction of flow of the condensate leading to the discharge opening 9 in the hot well so that the direction of flow of the drip discharge is the same as that of the condensate. Furthermore, the injector 13 extends adjacent to the discharge opening 9 and near the bottom of the hot well so that the drip discharge will mix with only a limited amount of the condensate in the hot well before passing through the discharge opening, the remaining part of the condensate in the hot well not being heated. As 35 40 45 shown, the injector is provided with apertures 14 in the periphery of its spherical enlargement, which permit of the passage of a limited amount of condensate into the injector to mix with the mixture of water and steam passing from the drips 10. 50 55 60 From the above description it is seen that the drip discharge is delivered into the condensate in the hot well under the surface of the condensate and preferably near the bottom of the hot well, so that the static pressure of the condensate above the point of entrance of the drip discharge will tend to prevent re-evaporation. Further, the entrance of the drip discharge is so located and directed that it will facilitate the motion of the condensate toward its discharge opening in the hot well, thereby tending to prevent the rise of the condensate heated by the drip discharge towards the free surface of the remaining condensate. 65 As shown in the modified construction in

Figure 2, the pipe 15 leading from the drips of the turbine extends into a pipe connection 16 and in the direction of flow of the condensate therethrough, this pipe connection being at a lower level than the hot well and being connected to the discharge opening in the hot well by means of the pipe connection 17. With this arrangement the static pressure of the condensate above the point of delivery of the drip discharge in the condensate is increased so that the re-evaporation temperature of the condensate at this lower lever is correspondingly greater. With this arrangement it is possible to run the condenser to closer temperature limits. 70 75 80

With the construction as shown in Figures 3 and 4, two hot wells 18 as well as two pumps 19 are provided for taking care of the condensate. The hot wells discharge into a chamber 20 which is connected with the pumps 19 so that either or both pumps may withdraw the condensate therefrom. With this construction it would be detrimental to arrange the discharge end of the pipe connected with the drips of the turbine 90 in such a way as to secure a directional flow toward either pump. By our arrangement we have provided means for delivering the drip discharge into the chamber 20 in such a way as to assist either or both pumps 95 properly withdrawing the condensate, or at least in such a way that the delivery of the drip discharge will not have a detrimental effect upon the pumps. Specifically, 21 is a pipe leading from the drips of the turbine 100 and 22 is the injector at the end of the pipe 21 and within the chamber 20, this injector being located intermediate the pumps 19 and so arranged that the drip discharge produces a vortex flow in the chamber 20, 105 the latter being preferably cylindrical in shape.

From the above description it will be readily seen that we have devised an arrangement which is a self-contained part 110 of the turbine and which automatically operates only when the turbine is in operation. Moreover, the heat of the drip discharge from the pressure stages of the turbine is saved by mixing the drip discharge 115 with the condensate. Further, by our particular method of delivering the drip discharge into the condensate only a limited portion of the latter is heated and this is withdrawn from the hot well before it can 120 rise to the surface of the condensate and cause a re-evaporation.

What we claim as our invention is:

1. The method of saving the heat in the drip discharge of a condensing prime mover, which comprises the delivering of the drip discharge into the condensate and below the surface of the latter and the using of the condensate as boiler feed water. 125
2. The method of saving the heat in the 130

5 drip discharge of the condensing prime mover, which comprises the delivery of the drip discharge into the condensate in the line of motion of the condensate toward its point of discharge and the use of the condensate as boiler feed water.

10 3. The method of saving the heat in the mixture of water and steam drained from a pressure stage of a condensing prime mover, which comprises the delivery of the mixture of water and steam into the condensate in such a manner that the mixture of water and steam facilitates the motion of the condensate toward a point of discharge 15 and also comprises the use of the condensate as boiler feed water.

20 4. The method of saving the heat in a drip discharge of a condensing prime mover, which comprises mixing the drip discharge with a limited amount of the condensate below the level of the latter and using the condensate as boiler feed water.

25 5. The method of saving the heat in a drip discharge of a condensing prime mover, which comprises the delivery of the drip discharge into the condensate in such a manner that that portion of the condensate heated by the drip discharge and also the drip discharge will be drawn from the 30 remaining portion of the condensate before the latter is heated and also comprises the use of the condensate as boiler feed water.

35 6. In a heat economizer for steam prime movers, the combination with a drip connection for a pressure stage of the prime mover, a condenser for the exhaust steam from said prime mover, and a reservoir for the condensate having a discharge opening, of means for conducting the drip discharge 40 from said connection into said reservoir and adjacent to said discharge opening, said condensate being used as boiler feed water.

45 7. The method of saving the heat in the drip discharge of a condensing prime mover, which comprises the mixing of the drip discharge with the condensate and maintaining a liquid seal between the point of mixing and the surface of the condensate exposed to the condenser and also comprises the using 50 of the condensate as boiler feed water.

55 8. The method of saving the heat in the drip discharge of a condensing prime mover, which comprises mixing the drip discharge with the condensate and maintaining a liquid seal between the point of mixing and the surface of the condensate exposed to the condenser, thereby raising the temperature of the condensate, and using the heated condensate for a purpose where the available 60 heat of said condensate is beneficial.

9. In a heat economizer, for steam prime movers, the combination with a drip for a pressure stage of the prime mover, a condenser for the exhaust steam from said prime mover, and a reservoir for the condensate, of means for conducting the drip discharge from said drip into said reservoir, and means for maintaining a liquid seal between the point of delivery of said drip discharge into said reservoir and the surface of the condensate exposed to the condenser, said condensate being used for a purpose where the available heat therein is beneficial. 65

10. The method of saving the heat in the drip discharge of a prime mover connected with a condenser, which comprises the delivering of the drip discharge without substantial change in its condition directly into the condensate formed by said condenser, withdrawing a mixture of condensate and drip discharge, and utilizing said mixture for a purpose where the available heat stored in said discharge is beneficial. 70

11. The method of saving the heat in the drip discharge of a condensing prime mover, which comprises the delivery of the drip discharge without substantial change in its condition directly into the condensate formed by said condenser, mixing said discharge with a portion of the condensate to raise the temperature of the latter, and withdrawing the condensate heated by said drip discharge, and utilizing the same for a purpose where a preheated liquid is beneficial. 80

12. The method of saving the heat in the drip discharge of a condensing prime mover, which comprises the mixing of the drip discharge with the condensate, maintaining a liquid column between the point of mixing and the condenser, and utilizing the condensate heated by said drip discharge for a purpose where a heated liquid is beneficial. 90

13. In a heat economizer for steam prime movers, the combination with a drip for a pressure stage of the prime mover, a condenser for the exhaust steam from said prime mover, and a reservoir for the condensate, of means for conducting the drip discharge from said drip into said reservoir below the surface of the liquid therein, and means for withdrawing from the reservoir the liquid containing the heat of said drip discharge. 100

110 In testimony whereof we affix our signatures.
